DESIGN FOR A BELT BUCKLE

Jacob Lewis Bibula, New York, N. Y.

Application July 22, 1939, Serial No. 86,174

Term of patent 3½ years

To all whom it may concern:

Be it known that I, Jacob Lewis Bibula, a citizen of the United States of America, residing in the city of New York, county of New York and State of New York, have invented a new, original, and ornamental Design for a Belt Buckle, of which the following is a specification, reference being had to the accompanying drawing, forming part thereof.

Fig. 1 is a plan view of a belt buckle showing my new design.

Fig. 2 is an edge view thereof.

My design is characterized by 3 elements comprising the same, the outer elements having V-shaped incisions at the outer ends and broad hooks at the inner ends which engage in a flat ring-like element in the manner as shown.

I claim:

The ornamental design for a belt buckle, substantially as shown and described.

JACOB LEWIS BIBULA.
